DEICING MEANS FOR AIRPLANES

Walter S. Diehl, United States Navy

Application December 4, 1937, Serial No. 178,095

6 Claims. (Cl. 244—134)

(Granted under the act of March 3, 1883, as amended April 30, 1928; 370 O. G. 757)

This invention relates to devices for preventing accumulation of ice upon airplanes or the like, and more particularly to the types of deicing means employing elastic coverings on the

5 leading edges of airfoils.

Heretofore, rubber sheeting, rubberized fabricated sheeting and the like, have been used as covers or overshoes on the leading edges of surfaces of airplanes that are exposed to ice forming conditions. Certain portions of these covers or overshoes were inflatable so as to break up the formations of ice, which are then removed by the force of the air stream. However, trouble has been encountered, especially at high speeds, 10 due to the area of negative pressure produced by the airfoil. This causes the sheeting to lift away from the surface of the airfoil and results in a flapping of the portion of the overshoe between the inflatable tubes and the line at which the overshoe is fastened to the surface of the airfoil. 15 This undesirable movement of the overshoe adversely affects the airfoil properties and sets up vibrations within the structure.

One of the objects of the present invention 20 is to avoid any flapping of the overshoe by equalizing the pressure on the under surface of the sheeting with that on its outer surface.

Another object of the invention is to provide 25 means for more positively holding the sheeting against the airfoil surface, by so constructing the overshoe that a greater negative pressure will be present on the under surface of the overshoe than on its outer surface.

A further object of the invention is to obtain 30 a lesser pressure on the overshoe's under surface by a source other than the construction of the overshoe itself.

With such objects in view, as well as other 35 advantages which may be incident to the use of the improvements, the invention consists of the parts and combinations thereof hereinafter set forth and claimed, with the understanding that the several necessary elements constituting the same may be varied in proportion and arrangement without departing from the nature and scope of the invention as defined in the appended 40 claims.

In order to make the invention more clearly 45 understood there are shown in the accompanying drawing means for carrying the invention into practical effect, without limiting the improvements in their useful application, which for purpose of explanation have been made the subject of illustration.

50 In the accompanying drawing:

Figure 1 is a section through the leading edge of an airfoil provided with an elastic sheeting or overshoe constructed in accordance with the present invention.

Figures 2 and 2A are plan views of Figure 1. 5
Figures 3 and 4 are sectional views of other forms of my invention.

Referring to the drawing, in Figure 1 the framework 10 and covering 11 of an airfoil are 10 shown. The leading edge of the airfoil is provided with an elastic overshoe 12, attached at its boundaries to the covering 11, in any well known manner, such as riveting, cementing, vulcanizing or lacing. The elastic overshoe 12 is provided 15 with a plurality of longitudinal slots or tubes 13 which may be intermittently inflated in manners well known in the art. The swelling of the slots or tubes 13 serves the purpose of breaking up or preventing the formation of ice on the airfoil. 20

In order to prevent flapping of the elastic overshoe 12, I have introduced a series of apertures 14 between the outer and under surfaces of the overshoe 12. Equalization of the pressure on the two surfaces of the overshoe 12 takes place 25 through the apertures 14.

Complete relief of the pressure requires reasonably free passage of air under the elastic overshoe 12. This is obtained by a plurality of knobs 15 or broken ridges 16. Figure 2 illustrates one pattern in which such knobs 15 may be arranged, while Figure 2A similarly shows one pattern or broken ridges 16. The knobs 15, broken ridges 16, or any other form of protuberances, or combinations thereof, may be arranged 30 in any desired pattern. The protuberances are so spaced relative to the thickness of the overshoe 12, the tension, and the pressure difference, that the intermediate panels of the overshoe 12 will not collapse and thereby act as valves 40 against the remaining area.

A modification of my invention as hereinabove described is illustrated in Figure 3. Slight protuberances 17 are provided on the outer surface 45 of the overshoe 12 about the apertures 14. These protuberances 17 may be of any desired shape such as a portion of a sphere, an approximate half-streamline, or a half-ellipsoid. They increase the thickness of the overshoe 12 by an 50 amount that will insure the mouths of the apertures 14 being above the remaining surface of the overshoe 12 even in the event of the overshoe 12 collapsing to the covering 11 between the knobs 15 or broken ridges 16. The protuberances 17, 55

being small, do not increase the drag due to the leading edge covering nor spoil the lift. The local increase in air velocity over the top of the protuberances 17 produces an increased suction 5 which is transmitted through the apertures 14 to the under surface of the overshoe 12, thus holding the sheeting tighter to the covering 11 of the airfoil as the speed increases.

In Figure 4 another form of my invention is 10 shown. The elastic overshoe 12 is provided with inflatable slots or tubes 13 and a pattern of knobs 15 or broken ridges 16 on its under surface as hereinabove described. Suction which will hold the overshoe 12 tightly against the covering 11 of the airfoil is obtained from an outside source 15 by connecting a series of pipes or tubes 18 to the area under the overshoe 12. These pipes or tubes 18 are spaced in the same manner as the apertures 14 of the other embodiments of this invention. The source of the suction transmitted by the pipes 18 may be a Venturi tube 19 in the air stream as illustrated, or any other low pressure source, such as a vacuum pump or a Venturi tube 20 in the engine exhaust.

25 The herein described invention may be manufactured and used by or for the Government of the United States of America for governmental purposes, without the payment of any royalties thereon.

30 I claim:

1. A deicing means for airplane surfaces exposed to ice-forming conditions comprising an expandable elastic covering secured to such surface and means for producing a lesser pressure on the 35 inner surface of said covering than on the outer surface thereof.

2. A deicing means for airplane surfaces exposed to ice-forming conditions comprising an expandable elastic covering secured to such sur-

face, said covering having a plurality of protuberances on the outer surface thereof, each of said protuberances having an aperture extending through the covering to permit air pressure to equalize on the inner surface thereof. 5

3. A deicing means for airplane surfaces exposed to ice-forming conditions comprising an expandable elastic covering secured to such surface, said covering having a plurality of protuberances on the outer surface thereof, each of said 10 protuberances having an aperture extending through the covering to permit air pressure to equalize on the inner surface thereof and a plurality of protuberances on the inner surface of said covering for maintaining said covering in 15 spaced relation to the surface to which it is secured.

4. A deicing means for airplane surfaces exposed to ice-forming conditions comprising an expandable elastic covering secured to such surface, and means connected with the space between 20 said covering and the surface to which it is secured for reducing the air pressure in said space below that on the outer surface of said covering.

5. A deicing means for airplane surfaces exposed to ice-forming conditions comprising an expandable elastic covering secured to such surface and means located in an area of relatively 25 low air pressure for lowering the air pressure on the inner surface of said covering. 30

6. A deicing means for airplane surfaces exposed to ice-forming conditions comprising an expandable elastic covering secured to such surface, and venturi means located in the slip stream of the airplane and connected with the space between 35 said covering and the surface to which it is secured for reducing the air pressure on the inner surface of said covering.

WALTER S. DIEHL.
